sponding shouldered portions of the recessed portions of said links, to exert a force tending to move said links inwardly towards each other.

9. In a cutter chain, a plurality of links, and means for pivotally connecting said links together comprising a plurality of split pins, each of said split pins being made up of two parts which are adapted to extend through adjacent ends of the links of the chain, a locking pin adapted to extend through one part of each of said split pins in the direction of its axis and be bent over at its ends to lock said parts of said split pin together, the other part of each of said split pins having recessed portions at its opposite ends, to

receive the bent-over ends of said locking pin, and said other part of each split pin having a head formed on each end thereof adapted to engage recessed portions of said links, to prevent turning movement of said split pin with respect to said links, the inner facing sides of said heads being inclined towards the transverse center of said split pin, forming inclined shouldered portions adapted to engage corresponding shouldered portions of the recessed portions of said links, to exert a force tending to move said links inwardly towards each other.
